UNITED STATES PATENT OFFICE.

SIGWARD PEDERSEN, OF CHICAGO, ILLINOIS, AND THOMAS SERNENDINGER, OF PHILADELPHIA, PENNSYLVANIA.

SAFETY DEVICE FOR RAILWAY-CARS.

SPECIFICATION forming part of Letters Patent No. 320,390, dated June 16, 1885.

Application filed June 9, 1884. (No model.)

To all whom it may concern:

Be it known that we, SIGWARD PEDERSEN, a resident of Chicago, Illinois, and THOMAS SERNENDINGER, of Philadelphia, Pennsylvania, both citizens of the United States, have 5 invented certain Improvements in Safety Devices for Railway-Cars, of which the following is a specification.

One object of our invention is to prevent injury to persons or property falling upon the track in advance of the wheels of a street-car or like vehicle, another object being to insure the quick stoppage of the car when there is an obstruction of any character upon the track. 15 These objects we attain in the manner herein-after set forth, reference being had to the accompanying drawings, in which—

Figure 1 is a longitudinal section of part of a street-car with our improvements; Fig. 2, 20 the same with some of the parts in a different position; Fig. 3, a transverse section of part of the car; and Fig. 4 a detached view, on a larger scale, of a brake-wheel, forming part of our invention.

A is part of the frame of the car, and B one of the axles of the same, to which, at the most available point, is secured a brake-wheel, D, preferably constructed as described herein-after. Beneath this wheel is a bar, F, hung 30 at the front end to a bracket, a, on the frame, and acted upon by a spring, b, which tends to depress it, the rear end of the bar resting upon a cam, d, on a rock-shaft, e, which is adapted to bearings in a hanger, i, and has an 35 arm, f, connected by a rod, g, to an apron, G, hung to the front portion of the frame, and of such length that its lower edge is but a few inches above the track. Under ordinary circumstances the apron hangs vertically, and 40 the bar F is free from contact with the brake-wheel, as shown in Fig. 1, but in the event of the apron meeting with any obstruction it is forced rearward, as shown in Fig. 2, thus, through the medium of the rod g and arm f, 45 operating the shaft e and its cam d, and causing the elevation of the bar F, the upper edge of the latter, which is preferably roughened, as shown, being thereby pressed forcibly against the brake wheel D, so as to prevent 50 the further rotation of the same and the axle and stop the car. Persons falling upon the

track are thus prevented from being crushed by the wheels, the tendency of the apron being to sweep them forward on or off of the track without injury while the car is moving 55 the short distance previous to its being stopped by the brake. Damage to valuable property falling upon the track is likewise prevented, while on the other hand the car cannot be derailed by contact of the wheels with obstruc 60 tions upon the track.

To prevent persons or property falling upon the track between the wheels, we use guards H, hung to the sides of the car and hanging down to within a short distance of the ground, 65 the front edges of these guards extending to the front of the car body and serving as guides for the apron G, projections m on the latter bearing on the ends of the guards H, as shown in Figs. 1 and 2. These guards H have openings H' for the axle-boxes B', as shown in Fig. 3. The lower edge of the apron, and preferably also that of each guard H, is furnished with a strip, p, of rubber or other elastic material, so as to relieve the shock 75 caused by striking any object upon the track, and prevent injury to the person by violent contact with the guard or apron.

Various forms of brake-wheel may be adopted—for instance, the wheel may be 80 clothed with wood or rubber; but we prefer a wheel made as shown in Fig. 4, in which s represents a block of rubber made in sections so as to be fitted to the axle and confined between opposite disks, t t, also made in sections 85 for convenience in fitting them to the axle, to which they are bolted or otherwise secured. The disks have internal prongs, y, which project into the rubber blocks and effectually prevent the turning of the same independently of the disks. Bolts, n, passing from disk to disk through the rubber block, also aid in preventing the block from turning, and serve to confine the disks laterally to the block and prevent spreading of the latter. 90 95

We claim as our invention—

1. The combination of the axle having a brake-wheel, D, the bar F, the pivoted apron G, and devices, substantially as described, whereby on the yielding of the apron the bar 100 is pressed against the brake-wheel, as set forth.

2. The combination of the apron G, the axle and its wheel D, the arm F, and the rock-shaft e, with cam d and arm f, connected to the apron, as set forth.

5 3. The brake-wheel D, consisting of the rubber blocks s and opposite disks, t, with prongs y, as set forth.

In testimony whereof we have signed our

names to this specification in the presence of two subscribing witnesses.

SIGWARD PEDERSEN.
THOMAS SERNENDINGER.
